UNITED STATES PATENT OFFICE.

CONYERS BUTTON, OF PHILADELPHIA, PENNSYLVANIA.

DESIGN FOR SCARF.

Specification forming part of Design No. **6,675**, dated May 27, 1873; application filed May 13, 1873.

To all whom it may concern:

Be it known that I, CONYERS BUTTON, of Philadelphia, Pennsylvania, have invented a Design for a Scarf, of which the following is a specification:

The figure in the accompanying drawing fully represents my design for a scarf, the remainder of the pattern being merely a repetition of that which appears.

Adjacent to each edge of the scarf is a longitudinal stripe, A, ornamented by the peculiar angular figuring shown, and at each side of this stripe is a narrower stripe, B, composed of three minor stripes ornamented by inclined rows of dots and by mottling, as shown. The central portion or body D of the scarf has

a peculiar mottled appearance imparted to it by short bars and dots distributed over the surface, substantially in the manner represented.

Irrespective of the colors employed, I claim—

The design for a scarf, substantially as described, and as represented in and by the accompanying drawing.

In testimony whereof I have signed my name to this specification in the presence of two subscribing witnesses.

CONYERS BUTTON.
